UNITED STATES PATENT OFFICE

SVERRE HILLAND, OF BROOKLYN, NEW YORK

CABLE CLAMP

Application filed November 6, 1928. Serial No. 317,663.

The object of my invention is to provide a clamp of this class which may be used with cables which are to be connected one with another or with cables used for truing buildings where the steel frame work has to be correctly positioned from time to time during the process of erection so that it may go up true. This object is accomplished by my invention, some embodiments of which are 10 hereinafter more particularly set forth.

For a more particular description of my invention, reference is to be had to the accompanying drawings, forming a part hereof, in which

15 Figure 1 is a side elevation of my improved clamp ready to be applied in truing a building or for any other similar purpose.

Figure 2 is an enlarged sectional view of the clamp and connected parts.

20 Figure 3 is a sectional view, taken on the line indicated by 3—3 of Figure 2, looking in the direction of the arrows.

Figure 4 is a plan view of a yoke.

25 Figure 5 is a perspective view of one of the clamp members.

Figure 6 shows a modified construction suitable where it is desirable to connect the ends of two cables without a splice.

Throughout the various views of the drawings, similar reference characters designate similar parts.

In the structure shown in Figures 1 to 5 inclusive, my improved clamp 1 is composed of a horseshoe bar 2 bent so as to form a loop 3 with converging ends 4, as indicated. Near their free ends, the bars 4 are notched at 5 so that they may spring outwardly and engage a yoke 6, as shown. The holes 7 through which these ends 4 pass are made a 30 little larger than the diameter of these ends so that these ends may be sprung together and then the yoke 6 may be removed or restored, or both, as desired. It will be observed from Figure 4 that the yoke 6 passes on one side only of the cable 8 which will be referred to below.

The ends 4 also carry the clamping members 9 and 10 which slide freely thereon and are connected by a metal dowel 11 which is 40 fixed to the clamp member 9 and slides free-

ly in a suitable perforation in the member 10, as indicated in Figure 3. The holes 12 through which the ends 4 pass are larger in diameter than these ends and are adapted to slide freely therein. The inner ends of 55 the clamp members 9 and 10 are provided with grooves 13 which are roughened, as shown in Figure 5, so as to form surfaces which are adapted to firmly grip the cable 8 which may be passed between them. 60

The loop 3 may be passed through a corresponding eyelet 14 of a turn-buckle 15 when the clamping members 9 and 10 and the yoke 6 have been removed from the ends 4. Thereafter these clamping members and 65 the yoke may be restored to the position indicated in Figures 1 and 2. When this has been done, the cable 8 may be placed over the yoke 6 and through the recesses 13 while the cable is held by hand in position. Thereafter 70 the clamping members 9 and 10 are slid in the direction of the yoke 6 and, when in position, are tapped by a hammer or similar instrument until they bind firmly. Once 75 they bind firmly on the cable 8, they fix the cable in relation to the clamp 1 so that it will not move until released. The cable may be released by tapping the clamps 9 and 10, either or both, so as to drive the same in the direction of the loop 3 and thereafter 80 the cable may be removed free of the clamp, as is obvious.

It is also obvious that the cable 8 may be provided at one end with a loop 16 and a hook 17 corresponding to the hook 18 which forms 85 a part of the turn-buckle 15. These hooks may be secured to any part of the metal frame of a building so as to plumb the same in the conventional manner.

It will be observed that in the practice of 90 my invention, it is unnecessary to reeve a cable through a loop 14, as has heretofore been the custom and then secure the loop by means of a clamp. Such is very objectionable because not only of the trouble incidental to 95 passing the cable through as indicated, but also because the sharp bend in the cable brakes the same as to some of the strands thereby making the cable a difficult thing to handle and the bends cannot be straightened 100

out so that it is impossible to coil the cables true. As the cables cannot be cut, it is sometimes necessary to pass long lengths through a loop 14 before the proper point is reached 5 where the loop is to be made. When my improved clamp is used no loop is made in the cable and the clamp may be applied anywhere. Furthermore, it can be set up and removed with no other instrument than a bar 10 or a hammer and it functions without nuts or bolts.

In the foregoing has been described a structure wherein the loop 14 is a part of the turn-buckle 15. Obviously, the loop 14 could be 15 like the loop 16, if desired, that is a portion of a cable without in any way changing the functioning of the clamp.

At times, it is desirable to connect the ends 20 of a cable for temporary purposes. When this is desired, the structure of Figure 6 is employed. Here there are two sets of clamping devices 9 and 10, two ends of cables 8, two yokes 6 and two bolts 19 with their ends bent to converge and the extreme ends are screw 25 threaded to receive nuts 20, as indicated. The cables 8 are inserted or detached precisely, as above described, and when in place, as indicated in Figure 6, they are firmly held.

While I have shown and described some 30 embodiments of my invention, it is obvious that it is not restricted thereto, but that it is broad enough to cover all structures that come within the scope of the annexed claims.

Having thus described my invention, what 35 I claim is:

1. A cable clamp having connected and converging bars, a yoke mounted near the free 40 ends of said bars and connected clamping members slidably mounted on said bars and adapted to be drawn together whenever they are shifted towards the yoke.

2. A cable clamp having connected and converging bars, a yoke connecting the free 45 ends of said bars and a clamping member having a cable receiving portion between two slidably mounted and connected members, one sliding on each of said bars.

3. A cable clamp composed of two converging bars, a yoke mounted near the free ends 50 of said bars, means for uniting the other ends of said bars, a clamping member slidably mounted on said bars and provided with cable gripping means and a guiding dowel connecting said gripping means.

In testimony whereof, I have hereunto set 55 my hand this 3rd day of November, 1928.

SVERRE HILLAND.
